or Seymour Earle

UNITED STATES PATENT OFFICE.

GEORGE H. MACLEAN, OF NEW HAVEN, CONNECTICUT.

BATCH-MEASURING HOPPER.

Application filed April 4, 1923. Serial No. 629,949.

To all whom it may concern:

Be it known that I, GEORGE H. MACLEAN, a citizen of the United States, residing at New Haven, in the county of New Haven 5 and State of Connecticut, have invented a new and useful Improvement in Batch-Measuring Hoppers; and I do hereby declare the following, when taken in connection with the accompanying drawings and the 10 characters of reference marked thereon, to be a full, clear, and exact description of the same, and which said drawings constitute part of this application, and represent, in—

Fig. 1 a top or plan view of a batch-measuring hopper constructed in accordance with 15 my invention.

Fig. 2 a front view of the same.

Fig. 3 an end view, with the hopper in its loading position.

20 Fig. 4 an end view of the same in the discharge position.

This invention relates to improvements in batch-measuring hoppers for use in loading sand and stone upon trucks for transportation to the place where they are to be mixed. 25 In the construction of concrete pavements and other concrete work, it is a common practice to draw the dry batches, consisting of the proper proportions of sand and stone, 30 from bins in auto trucks, the bodies of which are divided into compartments by partitions arranged transversely between the sides of the body. Each of these compartments is adapted to contain a predetermined 35 batch of stone and sand, together with a correct proportion of cement, and the object of this invention is to provide a hopper which will deliver these batches to a truck, and the invention consists in the construction as 40 hereinafter described and particularly recited in the claims.

In illustrating my invention, I have shown a measuring hopper designed for a three-compartment truck, but it will be understood that two compartments only may 45 be employed for loading two-compartment trucks.

As shown, the hopper 5 is divided into three compartments, and in each compartment 50 is a partition 6 forming three sets of chambers 7 and 8, one chamber of each set being adapted to receive sand and the other stone. The partitions 6 may be made adjustable, so as to vary the relative sizes 55 of the chambers 7 and 8. The chambers 7 and 8 of each compartment open into

mouths 9. Secured to opposite ends of the hopper are arms 10, which project below the lower end of the hopper and are mounted upon a shaft 11 supported in brackets 12 60 secured to inclined braces 13 forming part of the framework 14, which includes a platform 15, through which the hopper may be loaded from any source of supply. The mouths of the hopper are closed by a gate 16 65 extending across them and beyond each end, this gate being secured, at its upper edge, to the hopper, by hinges 17. The arms 10 are arranged in rear of a vertical plane through the hopper, so that the tendency of the hopper is to tip forward. This is resisted, while the loading operation takes place, by cables 18, which are fixed to the ends of the gate 16, and pass over sheaves 19 mounted in the frame 14 to a bar 20, this cable 18 also 70 holding the gate in the closed position. Connected with the arms 10 are cables 21, which extend over sheaves 22 to the bar 20, and on the bar are counter-balancing weights 23. It will be noted that when the 75 hopper is in its elevated or loading position, as shown in Fig. 3 of the drawings, that the cable 18 is taut, so as to firmly hold the hopper in place, and the gate in its closed position, while the cable 21 is slightly slackened. 80 Secured to the ends of the bar 20 are plungers 24 entering pipes 25 through stuffing boxes not shown, and these pipes 25 are connected through pipes 26 through a valve 27 with a standpipe 28, the pipes 25 and 26 85 being filled with suitable fluid to provide an hydraulic check for the upward movement of the bar 20. The position of the hopper, when it is being filled, is high enough so that the top of the truck-cab may pass 90 beneath it, and after the cab has passed beneath it, it may be tipped to discharge the contents into the truck, and this is done by opening the valve 27, allowing the fluid to rise in the standpipe 28 and permit the bar 95 to rise as the hopper tilts forward. As the hopper tilts forward, as shown in Fig. 4 of the drawings, owing to its inclination, the cable 18 becomes slack, so as to allow the gate 16 to swing open to permit the contents 100 of the hopper to be discharged. At this time the slack on the cable 21 is taken up, so that the hopper is supported by that cable. The counter-balancing weight is slightly heavier 105 than the weight of the empty hopper, so that, when the hopper is discharged, it is brought back into the filling position by the 110

downward movement of the bar 20 by the counter-balancing weights, the fluid in the standpipe 28 following down as the plungers 24 retire, and when the hopper is back in the 5 loading position, the valve 27 is closed until it is desired to again empty the hopper.

I thus provide, in a very simple way, a batch-measuring hopper adapted to discharge predetermined quantities of material 10 into separate compartments of a truck, and so arrange the hopper that it may be discharged and returned to its loading position by the operation of a single valve.

I claim:

15 1. A batch-measuring hopper, comprising a hopper having a plurality of compartments, each divided into chambers, said chambers having a common discharge-mouth, a hinged gate adapted to close said 20 mouths, said hopper pivotally mounted in a frame, cables connected with said hopper and with said gate, a counter-balanced bar with which said cables are connected, and hydraulic checks for the upward movement 25 of the said bar.

2. A batch-measuring hopper, comprising a plurality of compartments, each including two chambers, the chambers of each compartment having a common discharge- 30 mouth, a gate hinged to the hopper and adapted to close said mouth, said hopper provided at its ends with arms extending below its lower edge, a shaft on which said arms are mounted, a vertically-movable bar,

cables extending from said gate to said bar 35 and from the ends of said hopper to said bar, said bar provided at opposite ends with plungers, pipes into which said plungers extend, said pipes connected with a standpipe, and a valve therein controlling the 40 passage of fluid through said pipes.

3. A batch-measuring hopper, comprising a plurality of compartments, each divided into two chambers, each pair of chambers opening into a common mouth, a gate hinged at its upper edge to said hopper and adapted to close said mouths, said hopper pivotally mounted and adapted to tip forward and downward, a counter-balanced bar, cables 45 extending from the ends of the gates to said bar and from the sides of the hopper to said bar, said cables being so proportioned in length that when the hopper is in its loading position, the gate will be held closed but released when the hopper tilts forward, at which time the hopper is supported by cables attached thereto, hydraulic checks regulating the movement of said bar, a standpipe connected with said check, and a 50 valve in said connection.

In testimony whereof, I have signed this specification in the presence of two subscribing witnesses.

GEORGE H. MACLEAN.

Witnesses:

FREDERICK C. EARLE.

PAULINE M. F. EICHMANN.
